UNITED STATES PATENT OFFICE.

ALEXANDER C. HUMPHREYS, OF PHILADELPHIA, PENNSYLVANIA, ASSIGNOR
TO THE UNITED GAS IMPROVEMENT COMPANY.

APPARATUS FOR THE MANUFACTURE OF GAS.

SPECIFICATION forming part of Letters Patent No. 378,095, dated February 21, 1888.

Application filed January 25, 1886. Serial No. 189,615. (No model.)

To all whom it may concern:

Be it known that I, ALEXANDER C. HUMPHREYS, of Philadelphia, Pennsylvania, have invented a new and useful Improvement in 5 Apparatus for the Manufacture of Gas, of which the following is a full and true description, reference being had to the accompanying drawings, forming part of this specification.

My invention relates to those methods of 10 making gas in which, in addition to the water-gas generator, the injector for hydrocarbon oil, and the fixing-chamber, used in what is generally known as the "Lowe process," a retort-chamber is used containing open-ended retorts 15 filled with bituminous coal which is distilled by the heat of the gases from the generator, the coal-gas being mixed with the water-gas and the coke finally used in the generator.

In apparatus of this kind heretofore used the 20 retort-chamber is arranged so that the gases from the generator and from the retorts pass into and through it on their way to the fixing-chamber, and therefore no combustion is permissible in the retort-chamber when gas is being stored, and the retorts therefore begin to 25 lose heat as soon as the manufacture of gas is begun and give off less coal-gas than when the apparatus is being heated up. An undue proportion of this valuable coal-gas is therefore 30 burned up in preparing the apparatus for the manufacture of gas. In blowing up such apparatus the gases are burned in the retort-chamber and in the fixing-chamber, air being introduced at various points to meet the gases, 35 and as the completeness of the combustion depends on the volume of air thrown into the gases, it requires a very nice adjustment of the air-controlling valves to insure a proper proportionate combustion in the different 40 chambers.

The object of my invention is to overcome these difficulties and to provide a method of making gas which will, I believe, give better and more economical results than any heretofore designed.

My invention consists in combining, with a generator and fixing-chamber, a retort-chamber and a system of passages for the gas, one or more leading into the retort-chamber and 50 one or more directly into the fixing-chamber, whereby the supply of gas for each chamber

is independent of the other; in providing such a retort-chamber with an independent stack or escape for the gases, whereby a portion of the gases may be passed through this chamber and 55 burned there while the remaining gases are being stored; in arranging the stack or gas-escape of the retort-chamber so that it will cause a positive suction through the retort-chamber and so prevent, first, any tendency of the gases 60 from the retort-chamber to flow backward and mingle with the gases passing to the fixing-chamber; and, second, this positive suction tends to draw the gases from the retorts and generator and prevent the tendency, which they 65 would otherwise have, to flow out of the retort or generator doors when opened; in providing the gas-passage leading into the retort-chamber with a valve by which the proportionate quantity of gas admitted into the chamber 70 may be regulated at will; in arranging the openings of the gas-passages leading to the fixing-chamber above the opening leading to the retort-chamber, whereby the rich coal-gases pass directly into the fixing-chamber and the 75 generator-gas supplies the retort-chamber; and, finally, in the details of construction and arrangement hereinafter more fully described.

Reference being now had to the drawings, which illustrate my invention, Figure 1 is a 80 sectional side elevation of my improved apparatus on line *z z*, Fig. 6. Fig. 2 is a front elevation of the gas-passages and valve on the line *x x*, Fig. 4. Fig. 3 is a like view showing the valve open. Fig. 4 is a plan view of 85 the retort-chamber, partially cut away, so as to show the passage leading into the chamber and its controlling-valve. Fig. 5 is a similar view showing the valve open. Fig. 6 is a plan view of the retort-chamber on line *y y*, Fig. 1. 90 Fig. 7 shows in perspective my arrangement of gas-passages; and Fig. 8 is a rear elevation of the gas-passages, &c., on line *x x*, Fig. 4.

A is a generator of usual construction.

B is the retort-chamber; C, the fixing-chamber.

D D are retorts having doors *d* at their charging ends, and their inner ends, *d*, open.

E is a wall dividing the retort-chamber in two portions, one containing the body of the 100 retorts and the other, J, into which the ends *d* of the retorts open.

F and G are baffle-walls, which cause the gases in the retort to pass up, down, and again up around the retorts on their way to the stack H.

5 H' is a device by which a jet of steam may be thrown up the stack to increase the draft.

K, K', K², and K³ are air-pipes through which a blast is forced when desired.

L is the entrance of an air-passage leading 10 from the generator and chamber J to the retort-chamber. As shown, it enters horizontally, passes downward at L', and then upward into the retort-chamber at L².

M is a valve through which the flow of gas 15 into the retort-chamber is regulated.

M' is the handle of the valve.

N N' are gas-passages leading from the generator and chamber J to the passage O, leading to the fixing-chamber. These flues N 20 are situated above the passage L.

P is the inlet for the hydrocarbon oil, and R is the opening through which the gas leaves the fixing-chamber.

In using my invention a fire is made in the 25 generator of hard coal or coke, and the retorts D are charged with bituminous coal. An air-blast is turned into the generator through the pipe K, and the valve M is so placed that the rising gases shall pass in proper proportion 30 through the passage L and the passages N into the retort-chamber and fixer. The gases in the retort-chamber are ignited by air-blasts coming through pipes K' and K², arranged in any convenient positions, and the products of 35 combustion finally pass out of the stack H. The gases going to the fixer are also ignited by a blast through the pipe K³. As soon as the retorts become heated, they give off coal-gas at their open ends, d, and these gases mingle 40 with the gases from the generator and pass also through the flues L and N. When all parts of the apparatus have become sufficiently heated, the air-pipes K and K³ are closed, steam is turned into the generator at a', and oil is introduced at P in the head of the fixer. 45 As the water-gas is richer than the gas produced in blowing up, the valve M is pushed in to contract the opening of the flue L, and the air-blasts K' K³ are continued in the retort-chamber, the burned gases escaping 50 through the stack H. The heat of the retort-chamber may thus be maintained at the point of greatest efficiency, and, as the gas-flues N are above the flue L, the rich coal-gases pass 55 directly into the fixer and are saved.

When it is desired to open the generator or the retort doors d', the valve M should be opened to its fullest extent, so that the draft of the stack H, aided, if necessary, by the 60 steam-jet H', shall tend to create a vacuum in the generator and chamber J. The doors may then be opened without danger of the gases blowing outward.

I believe the construction of the apparatus 65 which is illustrated in the drawings to be that which embodies my inventions to the greatest advantage; but it may be modified in many

ways, and of course some of my improvements may be used without the others.

I am aware that in the patent granted to J. L. Stewart, June 10, 1884, and numbered 300,330, an apparatus is described in which a fixing-chamber is provided having retorts placed within it, through which the gases from the generator and the coal-distilling retorts 75 are pressed together with hydrocarbon vapors, a separate passage from the generator to this fixing-chamber being provided, through which gas may be constantly and in any desired quantity admitted and burned in said fixing-chamber to maintain the heat of the said fixing-retorts; but in the apparatus invented by me the chamber spoken of as the retort-chamber is of a totally different character from this fixing-chamber, being used in connection with the 80 open-ended retorts for distilling the bituminous coal and serving to keep up a uniform temperature in these retorts; and I desire it to be clearly understood that my invention relates solely to apparatus in which provision is made 85 to keep up combustion around these coal-distilling retorts.

Having now described my invention, what I claim as new, and desire to secure by Letters Patent, is—

95

1. In combination with a generator and fixing-chamber, a retort-chamber containing retorts for the distillation of bituminous coal, and a system of gas-passages, one or more leading into the retort-chamber and one or more direct to the fixing-chamber, whereby the supply of gases for each chamber is independent of the other.

2. In combination with a generator and fixing-chamber, a retort-chamber containing retorts for the distillation of bituminous coal, and having an independent stack or gas-escape and a system of gas-passages, one or more leading into the retort-chamber and one or more direct to the fixing-chamber, whereby the supply of gases for each chamber is independent of the other, and combustion may be continued in the retort-chamber while gas is being stored.

105

3. In combination with a generator and a fixing-chamber, a retort-chamber containing retorts for the distillation of bituminous coal, and provided with gas-supply passages independent of the passages leading to the fixing-chamber, and having an independent gas-escape provided with means for creating a strong 110 draft through the chamber.

115

4. In combination with a generator and a fixing-chamber, a retort-chamber containing retorts for the distillation of bituminous coal, and having a gas-supply passage independent of the passages leading to the fixing-chamber, and an adjustable valve whereby the quantity of gas admitted to said retort-chamber may be regulated at will.

125

5. In combination with a generator and fixing-chamber, a retort-chamber containing retorts for the distillation of bituminous coal, and having open-ended retorts opening into a

130

chamber or passage, J, a gas-passage leading to the combustion-chamber of the retort-chamber, and gas-passages leading to the fixing-chamber situated between the open ends of the 5 retorts, and the gas-passage leading to said combustion-chamber, whereby the coal-gases are substantially all conveyed to said fixing-chamber.

6. In combination with a generator, A, and 10 fixing-chamber C, the retort-chamber B, having a passage or chamber, J, situated over the

generator and divided from the combustion-chamber by a wall, E, through which the open-ended retorts D project, the passage L L' L², leading into the retort-chamber and having 15 valve M, the independent stack H, and air-pipes K' K², and the gas-passages N, leading to the fixing-chamber.
